[57] ABSTRACT

This invention relates to pure fluidic units and devices.

and more particularly to impedance-matching in pure fluid devices. Accordingly a pure fluid device is provided for the purpose of de-coupling one fluidic unit from another when they are staged. The fluidic de-coupler of the instant invention utilizes a novel two-sided vent design in the receiver line of the fluidic unit. Specifically, a square velocity profile is obtained in the receiver line by passing the flow in the receiver through an expanded portion of the line, that is, a plenum, then through a moderate contraction having a specified width W . Vents are then provided to either side of the receiver line down stream from the contraction, the vents having a width of $3W$. A catcher portion of the receiver line is disposed further down stream from the vents, the catcher portion having a width of $2W$, or double the receiver nozzle or contraction width. The square profile jet issuing from the nozzle of the receiver entrains about 100 percent flow over a $3W$ distance. This velocity profile does not decay over the distance of the actual vents provided in the de-coupler. This de-coupler design incorporating $2W$ as a width of the catcher is such to entrain substantially all of the flow. The de-coupler is designed such that the catcher length is $15W$. This catcher length maximizes the block load pressure recovery such that the flow distributes itself evenly in the catcher.

RIGHTS OF THE GOVERNMENT

The invention described herein may be manufactured, used, and licensed by or for the U.S. Government for governmental purposes without the payment to the inventor of any royalty thereon.

BACKGROUND OF THE INVENTION

It is of great concern to the fluidic designer to decouple one fluidic unit from another when they are staged. Heretofore, coupling devices for pure fluid units have not allowed full investigation of back load sensitive devices because previously only a portion of the P-Q curves could be examined since the unit would become either unstable or in a new state (flipped).

In the past in order to examine the full range of pressure flow, designers have put vents into the receiver lines of fluid amplifiers. This kind of venting, however, was not efficient in most cases and in others did not decouple well at all. Previously, designs of in line vents have incorporated bilaterally symmetrical vents perpendicular to the flow of fluid. Other designs have incorporated large plena tangential to the flow of fluid within the receiver line. And, even other types of units have incorporated vents in the operating region. None of these units de-couple with the respect to the uniqueness of the operating flow field. These units do, however, help in the flow recovery to some extent, but the fact that they only entrain on one side means that they are not as efficient in "jet pumping" as a symmetrical (two-sided) vent.

Fluids in fluid jet amplifiers have three significant properties; mass, viscosity, and compressibility. Aside from basic energy flux associated with the jets, significant manifestation of these properties include wave motions, energy dissipation, and gross turbulence. These phenomena are partially beneficial, and yet also introduce inherent limitations to the operation of fluid amplifiers.

Wave motion in fluid-amplifiers is a factor frequently causing unsatisfactory operation. Its mechanism is not well understood but the seriousness of the dynamic instabilities which result are clearly discernable. Most of these effects can be traced to the interaction of the amplifier with its inputs (source impedance-matching) or with its outputs (load impedance-matching).

In the design of fluid-amplifier systems, it is desirable that each amplifier or element in the system have matching impedances. Actually, the existing problem in the design of fluid system is feeding the output of a first device to the controls of a second device when the physical construction of the second device limits the flow below a certain value. Since the output dimensions of a given unit are generally larger than the controls, it becomes impossible to operate one into the other where two units are identical. Actually the second driven device, must be several times larger as a minimum. Without a dump, or bleed, the system becomes filled with fluid and ceases to operate.

Another problem is the loading effects in sensitive circuits, for example, a change in the load can be reflected to the interaction chamber of a fluid oscillator causing a change in frequency.

It is therefore an object of this invention to provide a new and novel means for de-coupling one fluidic unit

from another such that spurious signals are not exchanged between stages.

It is another object of this invention to provide a means for decoupling one fluidic unit from another wherein back stages are not loaded.

It is a primary object of this invention to provide a receiver decoupling means which optimizes a flow field such that only one flow field is utilized as opposed to an infinity of flow fields each depending on the downstream impedance.

It is yet an additional object of this invention to provide a new and novel fluidic receiver de-coupler which provides a square velocity profile at the end of the receiver.

It is still an additional object of this invention to provide a decoupling means for providing a velocity profile which will not decay appreciably over a short vent.

These and other objects of the present invention will become more fully apparent with reference to the following specifications and drawing which relate to a preferred embodiment of the present invention.

SUMMARY OF THE INVENTION

In accordance with this invention a new and novel two-sided vent decoupling for effectively de-coupling two stage fluidic elements is provided. The fluidic de-coupler of the instant invention utilizes a novel two-sided vent design in the receiver line. Specifically, a square velocity profile is obtained in the receiver line by passing the flow in the receiver through an expanded portion of the line, i.e., a plenum, and then through a moderate contraction having a width W. Vents are then provided to either side of the receiver line downstream from the contraction, the vents having a width of 3W. A catcher portion of the receiver line is disposed further downstream from the vents, the catcher portion having a width 2W or double the receiver nozzle contraction width. This arrangement provides a square profile jet which enables entrainment of about 100 percent flow over a 3W distance. The velocity profile does not decay over the distance of the actual vents provided. The particular catcher width utilized is such as to entrain substantially all of the flow. The catcher length is designed to be 15W. This particular catcher length maximizes the block load pressure recovery such that the flow distributes itself evenly in the catcher.

BRIEF DESCRIPTION OF THE DRAWING

The specific nature of the invention as well as other objects, aspects, uses, and advantages thereof will clearly appear from the following description and the accompanying drawings, in which:

FIG. 1 shows a fluidic dynamic de-coupler employing a plenum, a nozzle, oblique vents and a catcher in accordance with the teaching of this invention.

FIG. 2 (a) is a graph indicating the block catcher pressure recovery characteristics of the device versus pressure input.

FIG. 2(b) is a graph indicating catcher zero back pressure flow recovery characteristics of the de-coupling device as a function of pressure input.

FIG. 3 is a graph of the de-coupler efficiency.

DESCRIPTION OF THE PREFERRED EMBODIMENT

The device and design of the present invention will

be easily understood in its detail aspects by reference to FIG. 1 wherein there is shown a plane view of the design and passage ways incorporated into a pure fluid receiver decoupler. The pure fluid receiver-decoupler comprises essentially an input orifice 18, a channel 10 connected to plenum 15, a conduit, formed by tapered walls 31 and 32, interconnecting plenum 15 to nozzle 13, side vents 11 and 12, catcher 16, and vertical output vent 17.

Orifice 18 is provided for the purpose of connecting to the output orifice of a fluidic unit. Output vent 17 is provided for the purpose of connecting the receiver nozzle or input of a fluidic unit. Thus, by means of the pure fluid receiver de-coupler the fluidic unit connected to orifice 18 is de-coupled from a fluidic unit whose receiver input channel is connected at output vent 17. The pure fluid de-coupler is constructed such that input orifice 18 is connected to channel 10. Channel 10 is comprised of walls 30 which taper away from the central axis of orifice 18. This taper of wall 30 forms a plenum 15 near the termination of these walls. The plenum 15 is partially terminated by a short chamber area comprised of walls 31 and 32. These walls 31 and 32 converge and interconnect a nozzle 13 to plenum 15. Nozzle 13 is comprised of walls 31 and 32. Oblique vents 11 and 12 are juxtaposed to nozzle 13. These vents 11 and 12 are slanted toward input orifice 18. The vents 11 and 12 are bilaterally and symmetrically disposed with respect to the central principal axis of the chamber 10 and the nozzle 13. Walls 20 and 21 proximate to nozzle 13 join walls 33 and 34 of the nozzle 13 and form the outside surface thereof. The flow from the nozzle 13 is entrapped by catcher 16. Catcher 16 is symmetrically disposed about the axis of nozzle 13 and comprises walls 14 and 24. The end of the catcher 16 proximate to the nozzle 13 is terminated by walls 19 and 22 of vents 11 and 12, respectively. In particular wall 14 of catcher 16 is terminated by wall 19 of vent 11 and wall 24 is terminated by wall 22 of vent 12. The opposite end of catcher 16 is terminated by output vent 17. Output vent 17 is designed such that it is perpendicular to the flow from catcher 16 and comprises a cross section of round geometry.

Referring to FIG. 1 channel 10 interconnecting orifice 18 to plenum 15 is tapered such that it terminates at plenum 15 with a larger channel width than at orifice 18. The width of this termination of the channel 10 by walls 30 thereof is 3W where W is the width of the nozzle 13. Vents 11 and 12 comprise walls separated such that each vent has a channel width of 3W. Catcher 16 of the pure fluid de-coupler is designed such that walls 14 and 24 comprising said catcher each have a length of 15W. These walls 14 and 24 are separated by a distance of 2W.

The fluidic de-coupler of the instant invention, by utilizing a novel two sided vent design and plenum in the receiver line, conditions the velocity profile such that the profile issuing from the nozzle 13 is almost square and will not decay appreciably over the distance equivalent to the width 3W of the vents 11 and 12. The velocity profile entering channel 10 from orifice 18 is conditioned by passing the flow from orifice 18 through a plenum 15 and then through a moderate contraction provided by short tapered walls 31 and 32 connected to the walls of channel 10. A square profile jet is produced at nozzle 13 and as it issues from nozzle 13 en-

trains approximately 100 percent flow over the 3W distance of the vents 11 and 12. In anticipation of this entrainment the catcher width is designed as 2W, i.e., double the receiver nozzle width.

It is worthwhile to note that at zero catcher impedance additions or extensions of the catcher prevent flow spillage. On the other hand, increasing the distance between the catcher and the receiver nozzle provides more flow entrainment. The length of the catcher, which has been found to maximize the block load pressure recovery such that the flow may distribute itself evenly in the catcher, is 15W.

The pure fluid receiver de-coupler depicted in FIG. 1 has been found to have a blocked catcher pressure recovery of approximately 80 percent and a catcher zero back pressure flow recovery of approximately 210 percent. These characteristics are shown specifically in FIG. 2a and 2b, respectively. In FIG. 2 (a), curve A is a plot of pressure input to the catcher versus flow for zero back pressure and curve B is a plot of pressure input versus flow at the output of catcher 16 for zero back pressure. In 2(b) curve E represents a plot of pressure input versus output for catcher 16 when it is blocked.

FIG. 3 shows the effect of varying the downstream (output) pressure on input flow in pressure. Curve C shows the change in the pressure input as a function of a change in the pressure output. Curve D shows the change in the input flow with respect to a change in the pressure output. The efficiency of the pure fluid de-coupler depicted herein is approximately 98 percent.

It is to be understood that the inventor does not desire to be limited to the exact details of construction shown and described, for obvious modifications will occur to a person who is skilled in the art thereof.

I claim as my invention:

1. A pure fluid decoupler comprising an orifice for receiving fluid flow, a channel having nonparallel walls tapering away from the central axis of said orifice and sharply converging, a power nozzle disposed at the end of said channel comprising means for issuing a jet of fluid having a square velocity profile, a catcher forming a passage having a width greater than that of the nozzle axially disposed downstream from said nozzle, and at least two vents connected to said catcher and bilaterally disposed with respect to the axis of said catcher.

2. The pure fluid decoupler of claim 1 wherein said channel comprises a plenum connected to said power nozzle, whereby fluid passing through said channel also passes through said plenum.

3. The pure fluid decoupler of claim 2 wherein the greatest width of said channel is approximately three times that of said nozzle.

4. The pure fluid decoupler of claim 3 wherein the width of said vents is three times the width of said nozzle, and wherein the width of said catcher is twice the width of said nozzle.

5. The pure fluid decoupler of claim 4 wherein the length of said catcher is 15 times the width of said nozzle.

6. The pure fluid decoupler of claim 5 wherein said vents are further comprised of parallel walls.

7. The pure fluid decoupler of claim 6 wherein said catcher is comprised of parallel walls.
